UNITED STATES PATENT OFFICE.

ISIDOR KITSEE, OF PHILADELPHIA, PENNSYLVANIA.

TELEGRAPHY.

No. 847,188.

Specification of Letters Patent. Patented March 12, 1907.

Application filed June 18, 1906. Serial No. 322,330.

To all whom it may concern:

Be it known that I, ISIDOR KITSEE, a citizen of the United States, and a resident of the city and county of Philadelphia, State of Pennsylvania, have invented new and useful 5 Improvements in Telegraphy, of which the following is a specification.

My invention relates to telegraphy, and more especially to submarine and cable telegraphy or telegraphy over circuits in which the disturbing effect of electric capacity is great.

My invention relates particularly to the apparatus at the receiving end of such a cable or line, and resides in apparatus for relaying or translating into intelligible characters true reversals of current impressed upon the circuit at the transmitting-station.

It has been common practice in submarine telegraphy to employ a double key, whereby positive or negative impulses may be impressed upon the line at will. In such a system a dot is represented by an impulse of one polarity—say, a negative impulse—and a dash by an impulse of opposite polarity—say, a positive impulse. In such practice, however, it is found that such letters as "A N R" (Continental Morse) can be transmitted at relatively great speed and recorded plainly and distinctly, because in these letters dots and dashes alternate with each other, and therefore a negative impulse always follows a positive one, or vice versa. Thus one impulse clears the line for the next succeeding impulse of opposite polarity. In the transmission of letters, such as "H M O," &c., the speed is lower, in order to allow the cable to discharge itself, and the received record is indistinct and requires expert training to decipher it, for the reason that two or more dots or two or more dashes follow each other, necessitating two or more successive impulses of the same polarity.

It is the object of my invention to overcome these disadvantages and to make it possible to translate what I call "true reversals"—that is, impulses of substantially the same duration and intensity—successive impulses being of opposite polarity, and to relay or translate such impulses into intelligible records or messages.

It is the further object of my invention to so devise or arrange the receiving devices with the relay-circuit that the very feeble currents transmitted over the line or cable may be caused to operate the translating or

relaying device under the most trying conditions.

It has been found in transmitting over a cable from Penzance, England, to Canso, Nova Scotia, that while such letters as "H" and "O" required a certain length of time and were recorded by the siphon-recorder in uneven curves hardly distinguishable that when true reversals were transmitted much higher speed resulted, and the recorder curves were uniform in dimensions and clearly distinguishable from each other. It was also found that while the zero position of the instrument shifted when employing the old method no shifting of the zero was ascertainable when true reversals were transmitted.

In telegraphing over submarine cables or the like the insertion of a condenser in the circuit at the transmitting-station near the source of current is found to be of great advantage; but when it is attempted to relay the impulses impressed upon the line through such condenser it is found that the impulses are of such a short duration that the making or completion of a circuit through the contact parts of the receiving device, having a zero position, is not always productive of good results. The reason for this lies in the fact that an impulse due to the charge of the condenser is capable of moving the armature or other movable part of the receiver away from its zero position; but such impulse is not of long enough duration and strength to hold the moving contact part with sufficient power and sufficiently long against the stationary contact to properly control the electromagnetic means in the local circuit controlled by those contacts. To overcome this difficulty, I have recourse to an arrangement hereinafter described, and pointed out in the claims.

In the accompanying drawing I have illustrated diagrammatically the preferred form of my arrangement and I have made use of the well-known siphon-recorder construction as a polarized relay or receiving device. It is to be understood, however, that other receiving devices may be substituted, and that in place of the sounder any suitable recorder instrument may be employed.

It is the practice to connect the receiving device, such as a siphon-recorder or other electromagnetic device directly to the table or line. Since I make use of impulses of alternate polarity and of an arrangement in which the movable part of the receiving device can

move in one direction only, (prevented from moving in opposite direction by a stationary contact,) it is obvious that if such receiving device of mine is connected directly to the line an impulse of one polarity may move the movable part away from its zero position; but an impulse of opposite polarity will only press the movable part with greater force against the stationary contact; but it is my purpose that apparatus in a local circuit should be operated or controlled by arriving impulses of both polarities by breaking the contact of the receiving or relay device. To this end it is necessary to connect between the line and the receiving device or relay an intermediate device adapted to change the connection of the receiving device in its relation to the line or cable. I have here illustrated such intermediate device as a commutator serving as a pole-changer and operated by a step-by-step mechanism, and I have also connected the signal-translating instrument, such as a sounder, to a second commutator operated by the same step-by-step mechanism.

Referring to the drawings, Figure 1 is a diagrammatic view of receiving apparatus as coöperating with and controlled by a commutating device, and Fig. 2 is a side elevational view of the step-by-step mechanism.

In said drawing, 1 and 36 represent the line or cable to which the receiving apparatus is connected. The conductor 1 is connected with the brush 2, while the conductor 36 is connected with the brush 5. A coil 7, such as a siphon-recorder coil, is suspended in an intense magnetic field in the manner well known in siphon-recorders. The coil 7 carries the contact part or tongue 9 normally bearing against the stationary contact 10. One terminal of the coil 7 is connected through conductor 6 with the brush 3 and the other terminal through the conductor 8 with the brush 4.

The commutating device is cylindrical in form and comprises the ring portions 18 and 21, having projections extending toward each other, and comprises also the short contact-bars 19 and 20, which are cross connected, as shown at 35, so that the brushes 3 and 4 are alternately brought into electrical communication with the conducting-rings 18 and 21, and therefore with the brushes 5 and 2, which bear upon them.

An electromagnet 15 has its winding connected in circuit with a source of current, such as battery 14. The armature 16, normally held retracted by spring 38, carries pawl-like-projections which engage the teeth of the ratchet-wheel 17. When the electromagnet 15 is energized, the armature 16 will be pulled toward the core of said magnet and will accordingly move the ratchet-wheel through that part of the revolution represented by one tooth, and when the magnet is

deenergized it pulls the armature away from the core of the electromagnet 15 and the armature is then in readiness for the next operation. Such step-by-step mechanism is well known and understood in the electrical arts. Connection is also made from battery 14 through conductor 11 with the tongue or movable part 9 of the polarized relay or receiving device, and by means of conductor 12 it is connected with the stationary contact 10. A resistance 13 is connected in this last-traced circuit in order that the battery 14 shall not be completely short-circuited through the conductors 11 and 12 and the contacts 9 and 10.

The signal-translating instrument is here shown as a well-known sounder comprising the electromagnet 32, the armature-lever 34 carrying the armature 33, the spring 30 serving to hold the armature-lever in retracted position. 40 and 41 are the adjustable front and back stops. The winding of the magnet 32 is connected in circuit with the conductors 28 and 29, a source of current 31, and the brushes 25 and 26. The brush 25 bears upon the metallic ring 22 of a commutating device employed with the previously-described commutator and operated by the same step-by-step mechanism. Portions of insulating material 24 alternate with tongues or segments 23 of the ring 22. The brush 26 therefore is alternately in contact with one of the segments 23 or with the insulating-segments 24.

The operation is as follows: When the parts are at rest and in normal position—that is, when no impulse is flowing from the cable or line—the brush 26 is in contact with one or the other of the insulating parts 24 of the second commutator. The circuit of the electromagnet 32 is accordingly open, and the armature lever 34 is in retracted position, as shown in Fig. 1. When the step-by-step mechanism operates, the ratchet-wheel is moved through the angular distance corresponding with the width of one tooth, and the commutator is brought to such position that the brush 26 will be in contact with the one or the other of the conducting bars or segments 23. This will close the circuit of the magnet 32 and the armature-lever 34 will be attracted and held so attracted until after the next operation of the step-by-step mechanism when the brush 26 has left the conducting-bar and rests on an insulating-bar 24. It is well known that a polarized magnetic device, such as a siphon-recorder, is provided with means for determining a zero position. Such means usually comprises small weights or a very weak spring, the coil being centered in the field of powerful magnets. If with the parts in this centralized position a stationary contact is provided and so placed as to be in connection with the contacting arm or tongue secured to the moving coil, the adjustment can be made such that the

stationary and movable contacts are normally in good electrical connection. To this end the stationary contact may be adjusted in a manner commonly practiced in this art. Such is the preferred construction of the siphon-recorder type of relay or receiving device herein shown and described. When the contact arm or tongue 9 is in proper contact with the stationary contact 10, a circuit is formed through the conductors 11 and 12 and the resistance 13. The magnitude of the resistance 13 is much smaller than the resistance of the winding of the electromagnet 15. The current in dividing between the winding 15 and the circuit containing the resistance 13 will flow for the greater part through the circuit containing the resistance 13 and the contacts 9 and 10, and the amount of current flowing through the electromagnet 15 is insufficient to overcome the spring 38, and in effect, therefore, the electromagnet 15 remains deenergized. When the tongue 9 moves away from the contact 10, however, the circuit through the conductors 11 and 12 and the resistance 13 is broken, and the winding of the electromagnet 15 being no longer shunted by a relatively low resistance path the armature 16 is attracted and the commutators operated. So long as no impulse is received from the line or cable 136, the contact between 9 and 10 continues, and therefore the electromagnet 15 remains deenergized. Suppose the operator at the distant end of the cable or line impresses an impulse of one polarity—say, a positive impulse—and suppose the coil 7 to be connected in such manner that such positive impulse will move it in a direction to break the contact between 9 and 10. The instant such contact is broken the step-by-step mechanism moves the commutator through an angle corresponding with one tooth of the ratchet-wheel. The brush 4, which was formerly in communication with a bar or segment through brush 5, will then be brought into communication with a bar or segment connected with the brush 2, and the brush 3, which formerly was in communication with a bar or segment connected to brush 2, then comes into communication with a bar or segment connected with brush 5. In other words, the terminals of the coil 7 have become reversed with respect to the line-terminals. If now a negative impulse comes over the cable or line, the movement of the coil 7 will be in a direction the same as before and will break contact at 9 and 10. This for the reason that the impulse is in opposite direction, but the current through the coil is in the same direction, because it has had its terminals reversed. This operation is repeated for each impulse, so that for each impulse transmitted over the line or cable the contact is broken at 9 and 10; but these successive impulses being of opposite polarities the speed of signaling is materially increased, due to rapid line clearing. At the transmitting station the successive impulses are of alternate polarity, and the time interval between successive impulses determines the character to be transmitted—that is, a dot or a dash.

By this system the successive impulses are of opposite polarities—that is, an impulse of one polarity is always followed by an impulse of an opposite polarity. Furthermore, only a single impulse of one polarity is employed to transmit a symbol or character, the succeeding impulse of opposite polarity serving the double purpose of clearing the line and determining the time length of the character. Consequently the time elapsing between the symbol or character impulse and the clearing impulse determines the kind of character the operator wishes to transmit—that is, whether a dot or a dash.

Having now described my invention, what I claim as new, and desire to secure by Letters Patent of the United States, is—

1. In a telegraph system, the combination with a line-circuit, of a polarized receiving device, a local circuit controlled thereby, means included in said circuit for reversing the connections of said receiving device with respect to the line-circuit after each received impulse, a signal-translating instrument, a circuit including said translating instrument, and means for changing the condition of said circuit after each received impulse.
2. In a telegraph system, the combination with a line-circuit, of a polarized receiving device associated therewith, a local circuit controlled by said receiving device, and means included in said local circuit for reversing the connections of said receiver with respect to said line-circuit upon the receipt of each line impulse.
3. In a telegraph system, the combination with a line circuit, of a polarized receiving device, a commutator intervening between said line-circuit and said receiving device, a local circuit controlled by said receiving device, and means included in said local circuit for actuating said commutating device, whereby the relation of said receiving device to said line-circuit is reversed after the receipt of each line impulse.
4. In a telegraph system, the combination with a line-circuit, of a receiving device associated therewith, means for normally holding said receiving device in zero position, a local circuit controlled by said receiving device and normally closed thereby, and means included in said local circuit for altering the connection of said receiving device with relation to the line-circuit for each movement of the movable part of said receiving device.
5. In a telegraph system, the combination with a line-circuit, of a receiving device associated therewith, means for changing the relation of said receiving device with respect to

- 4
- said line-circuit after each received impulse, and a signal-translating instrument included in a local circuit and controlled by said changing means.
5. 6. In a telegraph system, the combination with a line-circuit, of a receiving device, a pole-changer intermediate said line-circuit and receiving device, a local circuit controlled by said receiving device, means in said circuit 10 for operating said pole-changer, a signal-translating instrument, a second local circuit containing the same, and means associated with said pole-changer for controlling said second local circuit.
15. 7. In a telegraph system, the combination with a line-circuit, of a polarized receiving device associated therewith, a pole-changer intermediate said line-circuit and said receiving device, means responsive to each impulse to shift said pole-changer, whereby said polarized receiving device responds similarly to alternate line impulses of different polarities.
8. In a telegraph system, the combination 25 with a line-circuit having relatively great capacity, of a polarized receiving device associated therewith, a pole-changer intervening between said line-circuit and said receiving device, means controlled by said receiving device for actuating said pole-changer upon the receipt of each line impulse, whereby said receiving device responds to succeeding line impulses of alternate polarity.
35. 9. In a telegraph system, the combination with a line-circuit having relatively great capacity, of a receiving device associated therewith, a pole-changer intervening between said line-circuit and said receiving device, and means controlled by said receiving device for actuating said pole-changer, whereby said receiving device has its connections automatically changed to respond alike to succeeding impulses of alternate polarity.
45. 10. In a telegraph system, the combination with a line-circuit having relatively great capacity, of a polarized receiving device associated therewith, a pole-changer intervening between said line-circuit and said receiving device, a local circuit controlled by said receiving device and containing means for operating said pole-changer, a second circuit including a signal-translating instrument, and means for controlling said second circuit 50 simultaneously with the movement of said pole-changer.
60. 11. In a telegraph system, the combination with a line-circuit having relatively great capacity, of a polarized receiving device associated therewith, a pole-changing commutator intervening between said line-circuit
- and said receiving device, a local circuit controlled by said receiving device and including means for actuating said commutator, a signal-translating instrument, a second local circuit controlling the same, and means operated simultaneously with said commutator for controlling said second local circuit.
12. In a telegraph system, the combination with a line-circuit having relatively great capacity, of a polarized relay associated therewith, the movable member of said relay comprising a coil adapted to be traversed by line impulses, a pole-changer for reversing said coil with respect to the line-circuit, a circuit controlled by said coil including means for actuating said pole-changer, whereby said relay responds similarly to succeeding line impulses of alternate polarity.
13. In a telegraph system, the combination with a line-circuit, of a polarized electromagnetic receiving instrument, and means for automatically reversing the connections of said receiving instrument with respect to said line-circuit after each line impulse.
14. In a telegraph system, the combination with a line-circuit, of a polarized receiving instrument, and means intermediate said line-circuit and said receiving instrument for reversing the connections of said receiving instrument with respect to said line-circuit after each line impulse.
15. In a telegraph system, the combination with a line-circuit, of a polarized receiving instrument, means intervening between said line-circuit and said polarized receiving instrument for reversing the connections of said receiving instrument with respect to said line-circuit, said reversing means being controlled by each line impulse, whereby said receiving instrument will respond similarly to successive line impulses of alternate polarities.
16. The combination with a telegraph line-circuit, of a polarized receiver associated therewith, and means for sending successive line impulses through said receiver in the same direction, whereby successive line impulses of opposite polarities actuate said receiver in the same direction.
17. The combination with a telegraph line-circuit carrying successive impulses of opposite polarities, of a polarized receiver, and means for sending the line impulses through said receiver always in the same direction.
